J. G. HORNIAK.

GATE FOR RAILWAY CROSSINGS.

APPLICATION FILED MAR. 11, 1914.

1,105,078.

Patented July 28, 1914

UNITED STATES PATENT OFFICE.

JOHN G. HORNIACK, OF HAWLEY, PENNSYLVANIA.

GATE FOR RAILWAY-CROSSINGS.

1,105,078.

Specification of Letters Patent. Patented July 28, 1914.

Application filed March 11, 1914. Serial No. 824,011.

To all whom it may concern:

Be it known that I, JOHN G. HORNIACK, a citizen of the United States, residing at Hawley, in the county of Wayne and State 5 of Pennsylvania, have invented certain new and useful Improvements in Gates for Railroad-Crossings, of which the following is a specification, reference being had to the accompanying drawings.

10 This invention relates to improvements in gates for railroad crossings, and more particularly to that class of gates which are operated by trains approaching the crossing.

15 An object of this invention is the provision of gates for railroad crossings which are operated by trains approaching the crossing, and which will automatically return to their normal positions after the train has passed the crossing.

20 A further object of this invention is the provision of gates for railroad crossings, in which the gates will be operated by trains approaching the crossing from either side thereof.

25 Still another object of this invention is the provision of railroad crossing gates, the operating mechanism therefor being simple in construction, and comprising a minimum number of parts, so that the same may be 30 quickly applied to use, and may be more cheaply manufactured than gates of this class heretofore used.

With these and other objects in view, my invention consists in the novel construction, 35 arrangement and combination of parts to be hereinafter more fully described, claimed, and illustrated in the accompanying drawings, in which—

Figure 1 is a side elevation of my device. 40 Fig. 2 is a top plan view thereof. Fig. 3 is a detail sectional view.

Referring more particularly to the drawing, the numeral 1 designates the rails of a railroad track, and 2 the gate posts arranged on opposite sides of the track to which gates 3 are pivotally connected near their inner ends. Pivotally mounted intermediate of its ends on a support 4 on one side of the track adjacent the inner end of 50 one of the gates, is a lever 5, and links 6 and 6' are provided having their ends pivotally connected to the inner ends of the gates 3, and one end of the lever 5 is pivotally connected to the link 6 intermediate of its ends. 55 The opposite or rear end of the lever 5 is provided with a downwardly extending pin

7, and disposed below the rails in vertical alignment with the rear end of the lever is a base 8 which is also provided with an upstanding stem 9. The pins 7 and 9 are normally spaced in vertical alignment with each other, and are adapted to receive the opposite ends of a coil spring 10 which normally maintains the rear end of the lever 5 above its pivotal point. The lower ends of the 60 links 6 and 6' extend below the rails of the track, and are connected to a shaft 11 which extends across the track below the rails. The inclined bar 12 extends along one rail of the track, the inner end of the bar normally extending above the tread surface of the rail, and is provided at its inner extremity with an inturned portion 13 by means of which the bar is pivotally connected to the rear end of the lever 5. 65

It will be seen from the drawing that when a train approaches the crossing in the direction of the arrow in Fig. 1 of the drawing, that the wheels of the train will engage the bar 12 which extends along the 70 track, so as to depress the same and therefore force the rear end of the lever 5 downwardly against the action of the coil spring 10. As the rear end of the lever 5 moves downwardly, the forward end thereof moves 75 upwardly, thereby moving the links 6 upwardly and closing the gates on each side of the track. To provide means for operating the gates upon the approach of trains from the opposite direction, the support 14 is provided below the rails of the track to 80 one side thereof, and pivotally connected to the support intermediate of its ends is a lever 15, one end of which is connected to the shaft 11 which connects the links 6 and 85 6'. Disposed below the opposite end of the lever is a support 15, which is provided with an upstanding stem 16, the lever being provided with a depending stem 17 in alignment with the stem 16, the stems receiving a coil spring 18 which normally serves to force the outer end of the lever 5 upwardly. A bar 19 is also arranged along 90 one of the rails on the opposite side of the crossing from the bar 12, the bar being also inclined upwardly and connected at one end to the outer end of the lever 15, so that upon approach of trains in a direction opposite that of the arrow, the gates will be 95 operated in the manner heretofore described. It will be seen that after a train has passed the crossing, the springs 10 and 100 105 110

18 will force the outer ends of the levers 5 and 15 respectively, upwardly to their normal position, thereby opening the gates so that vehicles and pedestrians may again 5 cross the tracks.

Having thus fully described the invention, what I claim as new and desire to secure by Letters Patent is:

1. The combination in gates for railroad 10 crossings, of posts upon opposite sides of the railroad track, vertically movable gates pivotally connected near their inner ends on said posts, a link depending from the inner end of each gate, a shaft connecting said 15 links, a lever pivotally connected intermediate of its ends to a suitable support, one end of said lever being pivotally connected to one of said links, and a bar arranged along one rail of the track, one end of said bar bearing upon the opposite end of said lever, 20 the bar being normally disposed above the level of the rail, so that the tread of a wheel of a train moving toward the crossing will depress the bar and actuate the lever to 25 lower the gates, as and for the purpose described.

2. The combination in gates for railroad 30 crossings, of posts on opposite sides of the railroad track, vertically movable gates pivotally connected near their inner ends to said posts, a link depending from the inner end of each gate, a shaft connecting said 35 links, a lever pivotally connected intermediate of its ends to a suitable support, one end of said lever being pivotally connected to one of said links, a bar arranged along one rail of the track and having one end thereof bearing against the opposite end of said lever, a yielding support arranged under said 40 opposite end of the lever to normally hold said bar above the level of the rail, as and for the purpose described.

3. The combination in gates for railroad 45 crossings, of posts upon opposite sides of the railroad track, vertically movable gates

pivotally connected near their inner ends to said posts, a link extending from the inner end of each gate, a shaft connecting said links, a lever pivotally connected intermediate of its ends to a suitable support, one end 50 of said lever being pivotally connected to one of said links, a bar arranged along one rail of the track and bearing at one end against the opposite end of said lever, a support arranged below said opposite end of 55 the lever, an upstanding pin formed on said support, a depending pin formed on said opposite end of the lever and arranged in vertical alinement with the first-mentioned pin, an expansion coil spring having its opposite ends engaged around said pins, said spring holding said opposite end of the lever in raised position to hold said bar above the level of the rail, as and for the purpose described. 60

4. The combination in gates for railroad 65 crossings, of posts arranged on opposite sides of the railroad track, vertically movable gates connected adjacent their inner ends to said posts, a link depending from the inner end of each post, a shaft connecting the lower ends of said links, levers pivotally connected intermediate of their ends to suitable supports arranged upon opposite sides of the crossing, one end of one of the 70 levers being pivotally connected to one of said links, one end of the other lever being pivotally connected to said shaft, bars arranged along one rail of the track on opposite sides of said crossing, one end of each 75 bar being engaged with the free end of one of said levers to normally hold said bars above the level of the rail, as and for the purpose described.

In testimony whereof I hereunto affix my 80 signature in the presence of two witnesses.

JOHN G. HORNIAK.
